UNITED STATES PATENT OFFICE

1,976,507

MANUFACTURE OF LOW BOILING
PETROLEUM DISTILLATES

Almer McDuffie McAfee, Port Arthur, Tex., assignor to Gulf Refining Company, Pittsburgh, Pa., a corporation of Texas

Application January 15, 1932, Serial No. 586,804

24 Claims. (Cl. 196—54)

This invention relates to manufacture of low boiling petroleum distillates, and it comprises a process of distilling higher boiling petroleum hydrocarbons, advantageously containing a substantial proportion of hydrocarbons of a naphthenic type, with the aid of anhydrous aluminum chloride, in which the said higher boiling hydrocarbons are first heated to just below cracking temperatures, are then mixed with a magma of aluminum chloride and oil of substantially constant composition and are continuously charged into a lower section of a body of heated oil contained in a heat insulated conversion chamber, the resulting low boiling distillates being condensed in a constricted zone in the presence of a dilute alkaline solution, the pressure, temperature and proportion of aluminum chloride in said conversion chamber being such as to keep the aluminum chloride and oil in liquid phase, to convert the said higher boiling hydrocarbons completely into the said low boiling distillates, coke and gases, and to hold the level of oil in the conversion chamber substantially constant; it also comprises a method of cooling and removing aluminum chloride coke from a conversion chamber in which method cool oil is used to displace the hot oil remaining in said chamber at the conclusion of a conversion run, water is employed to displace the said cool oil, the said water serving to disintegrate the said aluminum chloride coke, and the coke is substantially flushed from said chamber by water before the said chamber is opened to the atmosphere; and it also comprises certain organizations of apparatus elements suitable for feeding the said aluminum chloride magma and for carrying out the described process; all as more fully hereinafter set forth and as claimed.

As is well known, anhydrous aluminum chloride has several specific reactions upon heated mineral oils. One of the best known of these reactions is a conversion of higher boiling hydrocarbons into lower boiling distillates. This process is most frequently employed on high boiling distillates, and the resulting lower boiling distillates are known to be sweet smelling, saturated and stable. Various methods have been proposed to carry out this process, most of which have certain disadvantages. There are many difficult problems involved in carrying out such processes, several of which have never been satisfactorily solved heretofore.

I have found it advantageous to heat the oil, which is to be converted, to temperatures just below those required for thermal cracking and to mix this heated oil in a flowing stream with aluminum chloride just before passing the mixture into a heat-insulated conversion chamber.

It is advantageous to introduce this mixture at

the bottom of the conversion chamber rather than at the top. A somewhat higher yield is obtained and stirring in the conversion chamber is obviated, the latter always having been a troublesome and expensive operation. 65

It has also been found that, by correlating the temperature of the heated oil in the conversion chamber with the amount of aluminum chloride added, a substantially constant level of oil may be maintained in the conversion chamber, even 70 though the heated oil-aluminum chloride mixture is introduced at a constant rate.

A convenient method of adding aluminum chloride to heated oil has also been found. This consists in preparing a magma of aluminum 75 chloride and oil by mixing the two, with the aluminum chloride in excess, at temperatures in the neighborhood of 150° to 200° F, and adding this magma to the heated oil by displacing the magma with an equal quantity of oil, the 80 latter being thereafter employed to make up a new charge of magma. The magma prepared in this manner has been found to have a fairly constant composition of 80 per cent aluminum chloride and 20 per cent oil. Its composition is 85 so constant, in fact, that weighing of the aluminum chloride may be obviated, the volume of the magma added being a sufficient index of the weight of the chloride contained therein.

It has also been found advantageous to spray 90 an aqueous caustic solution into the distillate vapors coming from the conversion chamber just prior to introducing them into a condenser. This procedure prevents corrosion in the condenser coils. The caustic solution can be readily 95 separated from the condensed low boiling distillate and recycled after adding additional caustic to maintain its strength.

It has also been found that the above process is particularly advantageous for the production 100 of aviation gasoline when used on selected distillates, such as solar oil from Texas coastal crudes. In general it may be said that the type of distillate most advantageous is that derived from crude oils in which the so-called naphthenic type of hydrocarbons predominates. 105

The charging stock used with the best results thus far has the following tests:

Gravity: °A. P. I.	31-33	110
Over point: °F	365	
End point: °F	650	
Per cent at 392° F	10	
500	70	
590	90	115
50% at: °F	467	
Acid heat: °F	2	
Sulphur, (L): per cent	0.2	

The gasoline produced from this type of charging stock by this invention has a low gum con- 120

tent and an exceptionally high anti-knock value. A gasoline containing less than 4 mgs. of gum and having an octane number above 74 can be readily obtained. These characteristics set this 5 particular gasoline apart from gasolines in general and render it especially suitable as fuel for aeroplane motors. It may be said that there is little or no natural gasoline which meets the strict requirements of this type of service without 10 the addition of some foreign agent, such as tetra-ethyl lead, to give the required anti-knock value. The gasoline made by this invention can be advantageously blended with other types to produce a gasoline with intermediate 15 anti-knock values.

Other features of the present invention can be described more easily by referring to the accompanying drawing in which the figure represents, more or less diagrammatically, certain organizations 20 of apparatus elements within the purview of the present invention and useful in the performance of the described process. In this showing the single figure represents a diagrammatic, elevational view of the apparatus of the 25 invention, partly in section.

The main elements of the organization of apparatus shown in the figure comprise a tubular heater 2 located within a furnace 1, an aluminum chloride magma make-up tank 6, an 30 oil cylinder 8, two magma cylinders 9 and 10, a heat insulated converter or reaction chamber 14, a condenser 20, a distillate receiver 22, and a dilute caustic make-up tank 25. All of these 35 elements are inter-connected by suitably valved pipe lines in which are located the necessary pumps, etc.

The furnace 1 may be supplied with suitable heating means as at A—A. The tubular heater 2, located in this furnace is connected through 40 line 3 and pump 4 to an oil supply line 5 which in turn is connected to a source (not shown) of dry oil to be converted. Below the furnace 1 in the figure there is illustrated diagrammatically an aluminum chloride make-up tank 6, provided 45 with stirrer 39, in which tank the magma or sludge of aluminum chloride and oil is prepared. This make-up tank is connected to the oil line 32 by means of valved connection 7 and also to both the bottom and top of two magma cylinders 50 9 and 10 by the valved lines 44 and 46, respectively. The exit 12 of the magma cylinders and the exit 11 of the tubular heater 2 unite at the 4-way connection 28 which leads to the charge line 13 of the converter or still 14.

55 The converter 14 is provided with two manholes 15 and 16. At the bottom there is a valve 17 which may be opened for cleaning out purposes. The converter is also provided with coke line 33, credit oil line 31, water line 34, safety valve 36, try cock 30 and vapor line 18, on which is connected gauge 37. The vapor line 18 connects, through a pressure reducing valve 19, with the condenser 20 in which is located the condensing coil 38. The vapor line 60 65 is also connected, just before entering the condenser, with a dilute caustic line 21. All these connections are provided with suitable valves.

The exit of the condensing coil 38 is connected to a receiving tank 22. This receiving 70 tank has a connection 47 from which the distillate may be pumped to the usual steam stills (not shown) for producing gasoline. A top connection 48 is provided for removing gases and a lower connection 23 for drawing off caustic, by means of pump 24, to the caustic make-

up tank 25. The pump 29, connected to the exit of the caustic make-up tank is designed to deliver the dilute caustic either to the top of the condenser coil by means of line 21 or to the bottom of the still through caustic line 80 40 and charge line 13.

Coke pump 27 is attached to the bottom of the converter by coke line 33 and to a point near the top of the converter by credit oil line 31. Line 26, connected to the discharge side of this 85 pump leads to coke bins by branch 50 and to credit oil storage by branch 51. Credit oil storage is in turn connected to dry oil line 5 by connections not shown. Pump 27 may thus be used for pumping credit oil or coke to storage as well as for cooling the converter as hereinafter described.

When in operation the apparatus described is used as follows: Dry oil to be converted enters the oil line 5 and is pumped through the tubular heater 2, leaving through the line 11 at a temperature varying between 600° and 750° F., but advantageously close to 750° F. At the four-way connection 28, this hot oil meets the magma of aluminum chloride and oil which 95 is continuously pumped from the magma cylinders 9 and 10. The resulting mixture enters the converter 14 through the charge line 13 at the bottom. The vapors leave through the vapor line 18 at the top of the converter and 100 pass through the releasing valve 19 which is set at about 150 pounds gauge pressure. At this point the vapors, now at about 50 pounds pressure, meet a spray of a dilute caustic, such as a caustic soda solution, supplied through the 105 line 21 and pump 29. The vapors are condensed in the coil 38 and collect with the dilute caustic in the receiver 22, the distillate being thereafter sent to steam stills for the 110 production of gasoline. The dilute caustic solution is separated by gravity from the distillate in the receiver, being drawn off through line 23 and returned to the make-up tank 25, where it is reconstituted from time to time. Liquid caustic is added to this tank at 115 120 125 130 135 140 145 150

In the above process the proportion of aluminum chloride to the hot oil and the temperature of the latter are correlated in such a manner that the level of the oil in the converter remains substantially constant, for example at about the level of the try cock 30. If the level rises above this point, valve on line 130 130 135 140 145 150

31 may be opened and the oil run to credit through pump 27 and lines 26 and 51. The loss of any substantial amount of oil to credit means that the temperature and the proportion of aluminum chloride are not properly correlated. If the temperature or the proportion of aluminum chloride is raised slightly the tendency of the oil level to rise is immediately corrected. It is frequently convenient to regulate the temperature and the proportion of aluminum chloride in such manner that in each run there is a small but rather definite volume of oil run to credit. This serves to keep the conditions of the reaction on the safe side, so to speak.

The hot oil and aluminum chloride, in the above operations, are passed into the converter continuously until the coke which gradually builds up from the bottom has displaced nearly three fourths of the usual volume of oil. At 150

this point, which is indicated by the appearance of coke in credit oil line 31 and which commonly takes about 72 hours when a 40 foot converter 6 feet in diameter is employed, the converter is shut down to clean out the coke.

5 In cleaning the converter it must first be cooled down. Under ordinary conditions cooling would require a week or more but by the improved methods herein described cooling and cleaning have been found to require only 36 hours, the cooling period itself occupying only 8 to 12 hours. The development of efficient, safe and time saving methods for cooling the converter and for removing the coke represents one of the most difficult problems encountered in the successful operation of an aluminum chloride pressure still. Corrosion is difficult to avoid and practically prevents the use of steam for cooling purposes, due to the release of hydrochloric acid 20 by chemical reaction between the steam and the aluminum chloride coke. The coke in such a still frequently weighs 40,000 pounds. Any purely mechanical method of removing such a large mass from a confined space is bound to be difficult, time consuming and expensive. These difficulties have been overcome in a novel manner.

25 The cooling operation is carried out by shutting off the supply of hot oil and aluminum chloride to the converter and, by a suitable 30 setting of the valves in the various pipe lines, introducing a flow of cool oil into the bottom of the converter by means of pump 4, branch pipe 32 and charge pipe 13. This cooling oil passes out through the vapor line at the top of 35 the converter, runs through condensing coil 38, where it is cooled, thence to oil line 41, and is finally sent by pump 27 to credit oil storage where it may be again picked up by pump 4 and recirculated. The cooling oil is passed through 40 the converter in this manner until the latter is cooled below 212° F. Then dilute caustic from make-up tank 25 is introduced into the bottom of the converter by means of pump 29, dilute caustic line 40 and charging line 13, the valves 45 on these lines being properly adjusted for this circulation. The caustic solution displaces the oil upwardly and when it reaches the reducing valve 19 its flow is stopped. This caustic immediately neutralizes any hydrochloric acid 50 which forms upon contact of the aluminum chloride coke with the solution.

55 The caustic solution in contact with the aluminum chloride coke rapidly disintegrates the same. Within about 3 hours the coke is reduced to a soft pulp. At this time water is introduced 60 at a pressure of about 100 pounds through the water pipe 34, the coke and water being removed by the coke line 33 and coke pump 27. Lines 26 and 50 deliver the coke to storage bins. After 65 removal of the coke, the upper manhole is opened and the water drained out of the converter at the bottom. A hose may be introduced through the lower manhole 16 in order to wash down any remaining coke. The valve 17 may be opened 70 during the final cleaning and draining operations. After inspection, the converter is then ready for another run.

75 It will be noticed that, in the above cooling and coke removing operations, the conversion chamber is always full of liquid and is closed to the air until the aluminum chloride coke has been substantially removed from the chamber. It is well known that opening the chamber before this point is a highly dangerous operation. Considerable heat is generated upon the first

contact of water with aluminum chloride coke and, when this contact takes place in the presence of air and oil vapors, fires and explosions are difficult to prevent. The safety factor of the above described cooling process is an important factor in promoting its use.

80 At the start of a converting run the converter is cool and wet from washing out and removing the coke of a previous run. To commence a run the furnace 1 is fired and dry hot oil is introduced into the bottom of the converter through lines 11 and 13. The reducing valve 19 is left open and the hot oil soon evaporates all water which is driven off as steam and condensed in the coil 38. When the converter is thoroughly dry the reducing valve is closed. Hot oil is forced through the converter, (any excess being run to credit storage through line 31) until the pressure in the converter rises to about 75 pounds. At this time the oil fed to the converter is carefully regulated both as to rate of flow and temperature. The flow of aluminum chloride magma is then commenced in carefully regulated proportions. The pressure in the converter at this point rapidly rises to the value set on the 95 pressure reducing valve 19. Just before this valve opens the flow of caustic is started through the condenser coil by line 21 and pump 29. Then, as soon as the increasing pressure forces open the reducing valve, the run is started.

100 In one specific embodiment of the invention, which represents an actual commercial operation, a solar oil from a Texas coastal crude was fed at a temperature of about 750° F., to a 40 foot converter at a rate of about 35 barrels per 105 hour. The aluminum chloride magma, prepared at a temperature of 200° F. and containing about 9 pounds of aluminum chloride per gallon, was fed at a rate of 20 gallons per hour. A pressure of 110 115 pounds was maintained in the converter. This particular run was continued 72 hours. The run was then stopped for cleaning the converter. The distillate was produced at a rate of about 28 barrels per hour and had the following tests:

Gravity: °A. P. I.	40-42
Over point: °F.	94
End point: °F.	580
Percent at 221 °F	10 125
284	17
302	20
365	37
392	49
500	90 130
Acid heat: °F.	2
Sulphur, (L): percent	0.026

130 This distillate was transferred to steam stills for the recovery of its gasoline content, while the bottoms from the steam stills were returned to charging stock. The gasoline produced in this manner was sweet smelling, stable, saturated and had low gum and a high anti-knock value. It showed the following tests:

Gravity: °A. P. I.	61.5

15 The magma of aluminum chloride and oil used in the above described processes is prepared in the make-up tank 6, at a slightly elevated temperature. The anhydrous aluminum chloride is added to this tank through the man-hole 42. At the start of an operation oil is run into this tank through line 7. When the oil and aluminum chloride are thoroughly mixed, the magma cylinders are filled.

20 In order to fill magma cylinder 9, pump 43 is started. Valves 54 and 55 are then opened. The magma is thus pumped into the bottom of the cylinder 9, any air or oil which may be left in the cylinder from a previous operation being displaced upwardly and flowing to credit through 25 valve 63 or into the make-up tank 6 through valve 64. To fill magma cylinder 10, valves 56 and 57 are similarly opened while pump 43 is operating.

30 The magma from these cylinders may be fed into and mixed with the hot oil from line 11 as follows: The oil cylinder 8 may first be filled by opening valve 58 at the bottom of this cylinder. This allows oil from lines 32 and 49 to flow into and fill the cylinder, since it is suitably vented 35 to the air at the top. Then with valves 54, 55 and 58 closed and with valves 65, 59 and 60 open, the proportioning pump 45 is started. This pumps oil from cylinder 8 into the top of magma cylinder 9. This displaces the magma contained 40 in the latter cylinder downward and into line 12 from which it flows to the 4-way connection 45 28 joining the supply of hot oil from line 11 at this point and flows into the converter 14 through charge line 13.

50 When the oil cylinder is emptied by the pump 45 it is then known that all the magma in the magma cylinder is discharged since the volumes of the three cylinders 8, 9 and 10 are equal. At this point valve 58 may be again opened temporarily which quickly fills the oil cylinder again. Valves 61 and 62 are opened while valves 59 and 60 are closed. As soon as the oil cylinder is filled, valve 58 is closed. The oil in this cylinder now displaces the magma in cylinder 10 55 downward and into line 12. While this cylinder is being emptied into the converter, magma cylinder 9 may be refilled with magma. This is accomplished as outlined previously, the oil used for displacing the magma in the previous operation being displaced upwardly and run to credit through valve 63, with valve 64 closed, or it may be run into the make-up tank 6 through valve 64, where it may be used as fresh oil for making up additional magma.

60 It is thus evident that, by using the manipulations described, the three cylinders 8, 9 and 10 can be employed to feed magma into the converter continuously. The oil in cylinder 8 acts as a fluid piston in displacing the magma from cylinders 9 and 10. An important feature of

70 this procedure is that oil instead of magma passes through the proportioning pump 45. The amount of oil pumped is an accurate measure of the quantity of magma delivered. While a proportioning pump will deliver an accurate quantity of oil it cannot be used successfully over an extended period to measure and pump magma. The latter is too viscous and the abrasion caused by the aluminum chloride greatly reduces the life of such a pump. It is almost impossible to keep this type of pump in good working order when delivering magma. Thus both pump and gauging difficulties have been eliminated by the simple expedient of forcing the magma into the conversion drum by downward displacement with oil.

75 When the temperature of the aluminum chloride magma in the make-up tank is maintained constant and within a range of from 150° to 200° F., its composition is remarkably constant. When the temperature is maintained at about 200° F., for example, its composition is approximately 80 per cent aluminum chloride and 20 per cent oil. A gallon contains about 9 pounds of aluminum chloride. The weight of 80 the aluminum chloride, in such a magma need not be determined, the volume of the magma being a sufficient index of the weight of the chloride contained therein. Any variations in the composition are readily detected by the tendency of the oil level in the converter to rise or fall. If this level remains constant it is obvious that the aluminum chloride feed is correctly adjusted. The level can, in fact, be maintained constant by adjustment of the feed. 90 When this is done the oil fed into the converter is all converted into distillate, coke and so-called permanent gases, a balanced condition which is highly desirable.

95 It has been found that the hydrogen chloride and hydrogen sulfide developed in the converter do not cause any substantial corrosion until they reach the condenser coil and that this corrosion can be effectively obviated by spraying dilute caustic into this coil as described previously. This is an extremely simple method of 100 removing this source of annoyance and expense.

105 The specific conditions of operation outlined above may be varied to a considerable extent without departing from the purview of the invention. For example, the pressures employed in the process can be varied somewhat but are advantageously maintained somewhat above the point at which sublimation of aluminum chloride occurs. The oil must also be maintained in 110 liquid phase by pressure. The reaction used in this invention apparently does not occur in the vapor phase, and hence it is advantageous to prevent volatilization of the chloride.

115 While a satisfactory distillate is obtained by 115 distillation of oil with aluminum chloride at atmospheric pressure, the conversion is slow and the yield poor. The mixture of oil and aluminum chloride boils at about 500° F. If these temperatures and pressures are increased, the 120 time of conversion may be shortened to a few minutes and the yield increased 200 to 300 per cent. In the above described process pressures between 75 and 300 pounds per square inch have been found advantageous, while a suitable 125 pressure is 150 pounds.

130 The proportion of aluminum chloride to the oil charged, as used in the above specific example, is about 5 pounds per barrel (1.6 per cent by weight). This proportion may be varied be- 135

tween about 5 and 7 pounds per barrel (1.6 to 2.3 per cent by weight). Somewhat above 1 per cent or about 2 per cent is usually sufficient. As mentioned previously however, this quantity is advantageously correlated with the temperature of the hot oil in order to maintain a substantially constant level of oil in the converter. Temperatures ranging between 600° and 750° F. may be employed for the heated oil. These temperatures are somewhat below those required for thermal cracking. If the temperature is allowed to go high enough to cause thermal cracking, aluminum chloride appears to change its role from a converting to a polymerizing agent. Such temperatures are not ordinarily useful in the above described process.

The alkaline solution employed in washing the distillate vapors may be the same as that used for disintegration of the coke. Practically any dilute alkaline solution is suitable. Caustic soda solution with a concentration of about 3 to 4 per cent is advantageous. Caustic potash, sodium phosphate and soda ash solutions etc. are applicable. Milk of lime can be used if desired.

25 In the claims, the term "aluminum chloride" refers to anhydrous aluminum chloride.

What I claim is:

1. In the manufacture of low boiling distillates from higher boiling hydrocarbon oils, the process which comprises heating said higher boiling oils to temperatures slightly below those required for thermal cracking, adding somewhat above 1 per cent of aluminum chloride to the heated oils, feeding the mixture in a stream into a reaction zone containing a body of hot oil mixed with aluminum chloride, and there, without supplying additional heat thereto converting said mixture into distillate and coke and permanent gases at a rate corresponding to the rate of feed and allowing coke to build up in the said reaction zone; while the reaction zone and the point at which aluminum chloride is added are maintained under sufficient pressure to prevent sublimation of aluminum chloride and to keep the bulk of the unconverted oil in liquid phase.

2. The process of claim 1 in which the higher boiling hydrocarbon oils contain a substantial proportion of hydrocarbons of a naphthenic type.

50 3. The process of claim 1 in which the aluminum chloride added to the heated oils varies between 5 and 7 pounds per barrel of oil charged.

4. The process of claim 1 in which the aluminum chloride added to the heated oils amounts to about 2.0 per cent.

55 5. The process of claim 1 in which a pressure ranging from 75 to 300 pounds per square inch is maintained in said reaction zone and at the point where aluminum chloride is introduced.

60 6. The process of claim 1 in which the higher boiling oils are heated to a temperature between about 600 and 750° F.

65 7. The process of claim 1 in which the higher boiling oils are heated to a temperature of about 750° F.

70 8. In the manufacture of low boiling distillates from higher boiling hydrocarbon oils, the process which comprises heating a flowing stream of said higher boiling oils to a temperature in the neighborhood of 750° F., adding about 2.0 per cent of aluminum chloride to said flowing stream of heated oils and allowing the mixture to react in a reaction zone to produce coke, distillate and gases under a pressure of about 150 pounds per square inch, while neither supplying additional

heat to nor withdrawing coke from the said reaction zone.

9. In the removal of coke from an aluminum chloride converter, the process which comprises cooling the converter below 212° F. by displacement with cooling oil, displacing the cooling oil with a dilute alkaline solution and then drawing off and washing out the resulting coke pulp. 80

10. In an apparatus for making and feeding in a continuous stream a magma of aluminum chloride and oil, the combination of a magma make-up tank with an oil cylinder and two magma cylinders, the said magma cylinders being connected at both bottom and top to said make-up tank and the bottom of said oil cylinder being connected to the tops of said magma cylinders. 85

11. In the manufacture of low boiling distillates from higher boiling hydrocarbon oils, the process which comprises heating said higher boiling oils in a liquid flowing stream to temperatures slightly below those required for thermal cracking, adding somewhat above one per cent of aluminum chloride to the heated oils, feeding the mixture into a reaction zone maintained under pressures sufficient to prevent sublimation of aluminum chloride and to which no heat is supplied, and there substantially entirely converting said mixture into distillate, coke, and permanent gases, while not withdrawing any coke from the reaction zone. 95

12. The process of claim 11 in which a pressure ranging from 75 to 300 pounds per square inch is maintained over the said body of hot oil.

13. The process of claim 11 in which the higher boiling oils are heated to a temperature between about 600 and 750° F. 110

14. In the manufacture of low boiling distillates from higher boiling hydrocarbon oils, the process which comprises beating said higher boiling oils in a flowing stream under high pressures to temperatures slightly below those required for thermal cracking, adding a small amount of aluminum chloride to the heated oils, feeding the mixture into a reaction zone maintained under a pressure within the range from about 75 to 300 pounds per square inch and at a temperature not exceeding 750° F. and there continuously and substantially entirely converting said mixture into distillate, coke, and permanent gases, while not withdrawing any coke from the reaction zone. 115

15. The process of claim 14 in which a pressure ranging from 75 to 300 pounds per square inch is maintained over the said body of hot oil. 120

16. The process of claim 14 in which the higher boiling oils are heated to a temperature between about 600 and 750° F. 125

17. In the manufacture of low boiling distillates from higher boiling hydrocarbon oils, the process which comprises heating said higher boiling oils in a flowing stream under high pressures to temperatures slightly below those required for thermal cracking, adding somewhat above one per cent of aluminum chloride to the heated oils, feeding the mixture into a reaction zone maintained at a pressure above about 75 pounds per square inch, said reaction zone containing a body of oil and aluminum chloride, the mixture being fed into said reaction zone at a rate to maintain the level of said oil and aluminum chloride therein substantially constant, and there continuously and substantially entirely converting said mixture into distillate, coke, and 130

140

145

150

permanent gases, while not withdrawing any coke from the reaction zone.

18. In the manufacture of low boiling distillates from higher boiling hydrocarbon oils, the process which comprises heating said higher boiling oils in a flowing stream under high pressures to temperatures slightly below those required for thermal cracking, adding somewhat above one per cent of aluminum chloride to the heated oils, feeding the mixture into a reaction zone maintained at pressures sufficiently high to prevent sublimation of aluminum chloride without additional heat being supplied thereto, allowing conversion to take place in said reaction zone without agitation other than that supplied by the flowing stream of oil and without withdrawal of aluminum chloride coke, thereafter stopping the flow of the said mixture, reducing the coke to a pulpy mass by passing water into said reaction zone and then flushing out said pulpy mass.

19. In the conversion of high boiling petroleum oils into lower boiling petroleum oils, the process which comprises heating said higher boiling oils in a flowing stream to temperatures slightly below those required for thermal cracking, discharging the oil into a reaction zone maintained at pressures above 75 pounds per square inch and at temperatures not substantially exceeding 750° F., said reaction zone containing a body of oil and aluminum chloride, the mixture being fed into said reaction zone at a rate to maintain the level of said body therein substantially constant, continuously adding aluminum chloride to the heated oil in such quantity as will effect substantially complete conversion of the heavier oils to lower boiling distillate, coke and gases and will simultaneously effect maximum exhaustion of the aluminum chloride, and not removing spent aluminum chloride during the oil conversion step.

20. In the conversion of high boiling petroleum oils into lower boiling petroleum oils, the process which comprises continuously heating said higher boiling oils under high pressures to temperatures slightly below those required for thermal cracking, discharging the oil into an unheated reaction zone maintained under high pressure, continuously adding aluminum chloride to the heated oil in such quantity as will effect substantially complete conversion of the heavier oils to lower boiling distillate, coke and gases and will simultaneously effect maximum exhaustion of the aluminum chloride, and not removing spent aluminum chloride during the oil conversion step, continuing said oil conversion without agitation other than that supplied by the flowing stream of oil until said reaction zone is largely filled with spent aluminum chloride and coke, introducing cool oil into the reaction chamber and circulating such cool oil through said chamber until the temperature of the contents thereof has fallen below 212° F., then introducing a dilute alkaline solution into the chamber and gradually displacing all of the oil thereby, and finally flushing the said alkali and the spent aluminum chloride and coke from the chamber.

21. In the manufacture of low boiling distillates from higher boiling hydrocarbon oils, the process which comprises heating said higher boiling oils in a flowing stream to temperatures slightly below those required for thermal cracking, adding somewhat above one per cent of aluminum chloride to the heated oils, feeding the mixture into a reaction zone maintained

below thermal cracking temperatures, and at pressures sufficient to prevent sublimation of the aluminum chloride and to maintain the bulk of the unconverted oil in liquid phase, and there continuously and substantially entirely converting said mixture into distillate, coke and permanent gas, and withdrawing nothing but distillate and permanent gas from the reaction zone until a substantial quantity of coke has accumulated therein.

22. In the conversion of high boiling petroleum oils into lower boiling petroleum oils, the process which comprises continuously heating said higher boiling oils under substantial pressure to a temperature slightly below that required for thermal cracking, discharging the oil into an unheated reaction zone maintained under substantial pressure, continuously adding aluminum chloride to the heated oil in such quantity as will effect substantially total conversion of the heavier oils to lower boiling distillate and coke and gas and simultaneously effect maximum exhaustion of the aluminum chloride, and not removing spent aluminum chloride during the oil conversion step, continuing said oil conversion until said reaction zone is largely filled with spent aluminum chloride and coke and is substantially free of oil, introducing cool oil into the reaction chamber and circulating such cool oil through said chamber until the temperature of the contents thereof has fallen below 212° F., then introducing a dilute alkaline solution into the chamber and gradually displacing all of the oil thereby, and finally flushing the said alkali and the spent aluminum chloride and coke from the chamber.

23. In the conversion of high boiling petroleum oils into lower boiling petroleum oils, the process which comprises continuously heating said higher boiling oils under high pressures to temperatures slightly below those required for thermal cracking, discharging the oils into an unheated reaction zone maintained under high pressures, continuously adding aluminum chloride to the heated oils in such quantity as will effect substantially complete conversion of the heavier oils to lower boiling distillate, coke and gases and will simultaneously effect maximum exhaustion of the aluminum chloride, and not removing spent aluminum chloride during the oil conversion step, continuing said oil conversion without agitation other than that supplied by the flowing stream of oil until said reaction zone is largely filled with spent aluminum chloride and coke, introducing cool oil into the reaction chamber and circulating such cool oil through said chamber until the temperature of the contents thereof has fallen below 212° F., displacing the cooling oil by means of an aqueous liquid, thereby decomposing the spent aluminum chloride coke, and finally flushing the spent coke from the chamber.

24. In the conversion of high boiling petroleum oils into lower boiling petroleum oils, the process which comprises continuously heating said higher boiling oils under substantial pressure to a temperature slightly below that required for thermal cracking, discharging the oil into an unheated reaction zone maintained under substantial pressure, continuously adding aluminum chloride to the heated oil in such quantity as will effect substantially total conversion of the heavier oils to lower boiling distillate and coke and gas and will simultaneously effect maximum exhaustion of the aluminum chloride, and not

removing spent aluminum chloride during the oil conversion step, continuing said oil conversion until said reaction zone is largely filled with spent aluminum chloride and coke and is substantially free of oil, introducing cool oil into the reaction chamber and circulating such cool oil through said chamber until the temperature of

the contents thereof has fallen below 212° F., displacing the cooling oil by means of an aqueous liquid, thereby decomposing the spent aluminum chloride coke, and finally flushing the spent coke from the chamber.
